UNITED STATES PATENT OFFICE

98,206

DESIGN FOR A SHOW CASE

Frank L. Pollard, Oakland, Calif.

Application February 20, 1935, Serial No. 55,519

Term of patent 3½ years

To all whom it may concern:

Be it known that I, Frank L. Pollard, a citizen of the United States, residing at Oakland, in the county of Alameda and State of California, have invented a new, original, and ornamental Design for Show-Cases, of which the following is a specification, reference being had to the accompanying drawing, forming part thereof.

Figure 1 is a top plan view of a show-case, showing my new design.

Figure 2 is a front elevational view of the show-case.

Figure 3 is an end elevational view of the show-case.

The solid black strip appearing at the bottom edge of Figure 3, at the extreme ends of Figure 1, and at the lower corners of Figure 2, is a kick-board, of a color contrasting with the body portion, which overlies the surface of each end panel adjacent its lower edge.

I claim:

The ornamental design for a show-case, as shown and described.

FRANK L. POLLARD.
